PRESSER ARRANGEMENT FOR WARP
KNITTING MACHINES

Herbert Wirth, Hartmannsdorf, near Chemnitz,
Germany, assignor to the firma Emil Wirth
Wirkmaschinenfabrik, Hartmannsdorf, near
Chemnitz, Germany

Application February 13, 1937, Serial No. 125,658
In Germany February 22, 1936

4 Claims. (CL. 66—98)

The present invention relates to an alternately acting presser device for warp knitting machines.

As is well known, in warp knitting machines provided with a plain presser and a pattern presser the plain presser is slidably arranged with regard to the pattern presser in such a manner, that the plain presser, when shifted slightly beyond the pattern presser, acts upon all the frame needles, whereas, if the plain presser is withdrawn, such bearded needles only are pressed which are acted upon by the exposed pattern presser. The pattern presser, therefore, permanently engages the bearded needles which accordingly are pressed by the pattern presser even if tuck patterns are not produced.

Now, the object of the invention is to provide a pattern presser for warp knitting machines in which the one or the other presser only is rendered operative at any time. The change of the two pressers is effected positively, whereby a reliable operation, and therefore, higher speeds of operation are obtained.

To obtain the desired end, the pattern presser as well as the plain presser are, according to the invention, arranged to be positively rendered operative and inoperative. The two pressers are provided at one and the same holder and may be shifted in opposite directions. They are arranged with regard to each other under such an angle of inclination, that both of them have the same point of pressing at the bearded needle.

In the accompanying drawing an alternately acting presser device according to the invention is shown by way of example.

35 In this drawing:

Fig. 1 is a cross section through a portion of a warp knitting machine provided with an alternately acting presser device according to the invention.

40 Fig. 2 is a sectional detail elevation.

Fig. 3 is a plan view of a detail and

Fig. 4 is an elevation of the device shown in Fig. 3 partly in section.

Fixed upon a holder 1, reciprocated in the ordinary manner by the cam shaft of the warp knitting machine, is the bearing 2 for the plain presser 3. The latter is, by means of an intermediate link 4, connected to an eye 5 which is provided on a joint member fixed upon a shaft 6 journalled in the holder 1. Due to this construction the plain presser may be reciprocated upon the bearing 2. The front portion of the presser 3 is flattened. Approximately diametrically opposite the eye 5 a second eye 7 is fixed to

the joint member, and this second eye 7, is by means of an intermediate link 8, connected to the pattern presser 9. The latter is slidably arranged upon the flattened portion of the plain presser 3. Fixed upon the shaft 6 is a fork 10 carrying at the end of each prong a roller 11 and 12 respectively.

Below the shaft 6 another shaft 13 is journalled in the holder 1. This shaft 13 may be reciprocated in any well known and suitable manner and carries a double cone 14 shown in detail in Figs. 3 and 4. The rollers 11 and 12 are adapted to run upon the peripheral surface of this double cone 14. The bolts screwed into the prongs of the fork 10 and carrying the rollers 11 and 12 are in the longitudinal direction of the shafts 6 and 13 separated from each other by such a distance that, as shown in Figs. 3 and 4, the roller 12 engages the portion of the double cone 14 having the smallest diameter if the roller 11 runs upon the portion of the cone having the largest diameter and vice versa.

If the plain presser is operating, the roller 11 runs upon the portion of the double cone 14 having the largest diameter and all members carried by the holder 1 are moved in the usual manner towards the bearded needles 15 to press the latter. The pattern presser 9 hereby participates in the movements of the plain presser without, however, coming to action.

If now tuck patterning is to be produced, the shaft 13 is shifted in its longitudinal direction in such a manner, that the roller 11 engages with the portion of the double cone 14 having the smallest diameter, whereas the roller 12 cooperates with the portion of the double cone 14 having the largest diameter. Hereby the fork 10 carrying the rollers 11 and 12 is rocked. Due to the fork 10 carrying the rollers being fixed by means of a screw 16 upon the shaft 6, the latter 40 also is rotated in the same direction, whereby the eyes 5 and 7 are rocked in such a manner, that the plain presser 3 is withdrawn and simultaneously the pattern presser 9 is advanced. The plain presser 3 is, during the movement of 45 the holder 1 towards the bearded needles 15, prevented from reaching the bearded needles so that those bearded needles 15 only can be pressed which lie opposite the pattern presser 9. In this manner tuck patterns are produced.

If it is desired to again operate with the plain presser, it is only necessary to shift the shaft 13 in the opposite direction, whereby the plain presser 3 is automatically and positively moved into the position ready for pressing the bearded

needles 15, whereas simultaneously the pattern presser 9 is withdrawn out of the range of the bearded needles.

The flattening of the plain presser 3 is so chosen as to serve as bearing for the pattern presser and on shifting of the pattern presser into the operative position to allow the latter to operate upon the same point of the bearded needles as the plain presser. The shaft 13 may 10 be shifted in a manner similar to that employed in the shifting of the lapping machine.

What I claim is:

1. An alternately acting presser device for warp knitting machines, comprising a plain presser, a holder carrying said plain presser, a pattern presser also carried by said holder, a shiftable shaft journaled in said holder, a double cone fixed upon said shiftable shaft, a second shaft rotatably mounted in said holder, a joint member fixed to said rotatable shaft, a link connecting said joint member with said plain presser, a

second link connecting said joint member with said pattern presser, a fork fixed to said rotatable shaft, and a roller provided at each prong of said fork, said rollers being adapted to cooperate with said double cone. 5

2. In a device as set forth in claim 1 in which eyes are mounted at diametrically opposite points on said joint member and are connected to said links connected to said plain presser and pattern presser respectively. 10

3. In a device as set forth in claim 1 in which said plain presser and said pattern presser are arranged with respect to each other under such an angle of inclination, that both pressers act upon the same point of pressing at the bearded 15 needles.

4. In a device as set forth in claim 1 in which said plain presser has a flattened portion upon which said pattern presser is adapted to slide. 20
